UNITED STATES PATENT OFFICE.

MYRON W. CLARK, OF PARMA, ASSIGNOR TO GEORGE T. SMITH, OF JACKSON, MICHIGAN.

CONVEYER FOR FLOUR-BOLTS.

SPECIFICATION forming part of Letters Patent No. 319,786, dated June 9, 1885.

Application filed December 1, 1883. (No model.)

To all whom it may concern:

Be it known that I, MYRON W. CLARK, a citizen of the United States, residing at Parma, in the county of Jackson and State of Michigan, have invented certain new and useful Improvements in Conveyers for Flour-Bolts, of which the following is a specification, reference being had therein to the accompanying drawings.

Figure 1 is a longitudinal section taken on line xx , Fig. 2. Fig. 2 is a transverse section taken on line yy , Fig. 1. Fig. 3 is a detached view of one of the chutes. Fig. 4 shows a modification. Fig. 5 is a transverse section, on a diminished scale, of the lower portion of a flour-bolt having my invention applied thereto.

$A A'$ are the gather-boards or cant-boards, arranged below the bolt, which is represented by A' . These gather-boards are joined at their upper ends to the outer casing-walls, $A^2 A^2$, of the bolt, and inclined downwardly and inwardly toward the center-board, so as to form a longitudinal throat above the center-board, extending practically the entire length of the bolt-chest. Each of these boards is provided upon its lower edge with a series of transverse slots, $a a'$.

$B B C$, respectively, the outer side boards and the center-boards, which, with the ends $E E$, constitute conveyer-boxes arranged below the gather-boards, whose lower edges are a short distance apart, so as to provide a throat for the passage of material to the conveyers.

$F F'$ are the conveyers, of any usual or approved construction, having the ends of their shafts journaled in the end boards, $E E$, or in boxes secured thereto.

$G G$ are swinging covers hinged at the upper edges to the gather-boards, with their lower edges resting upon the upper edges of the side boards, $B B$.

$H H$ are partition-bars, substantially triangular in cross-section, arranged at suitable intervals, with their ends supported upon the cant-boards. Each bar is slotted longitudinally upon its under side, as at h , the bars being so arranged upon the cant-boards that each slot h coincides with two slots, a , in the gather-boards, for a purpose which will be explained.

$I I' I'$ indicate, respectively, the bottom and sides of the vibrating chutes. Each side portion, I' , is of substantially triangular shape, and arranged at a right angle to the plane of the bottom portion, I .

$i i$ are holes for the reception of bolts c , by means of which the chutes are suspended from the partition-bars $H H$, in such position that the edges of the triangular sides $I' I$ can be inserted in the slots a when the chutes are in the position shown in the drawings, and are therefore in proper working relation to the cant-boards and the conveyers, thus insuring that no material can pass down between the upper edges of the sides of the chutes. By an examination of the drawings it will be readily understood that the bottoms I of these chutes form practically continuations of the cant-boards, and that they (the chutes) can be arranged to deliver material to either of the conveyers alternately. Thus when the end of a chute is placed in contact with or in close proximity to the under surface of the cant-board A , such material as passes on to the chute will be delivered to the conveyer F , and vice versa. In my invention the upper edges are formed on straight lines, and therefore the blanks from which the chutes are made may each be bounded by straight lines, and the chutes may be pivoted to the partition-bars by the use simply of bolts or pins passing through holes in the bars and through the upper corners of the sides of the chutes.

I do not wish to be limited to forming the partition-bars and the lower edges of the gather-boards with slots in them, because under some circumstances they might be dispensed with, and the chutes pivoted to ears h' projecting downwardly from the bars, as indicated in Fig. 4, although I prefer the construction shown in the other figures, because, among other things, the friction between the sides of the chutes and the adjacent walls of the slots assists in maintaining them in proper position after they have been adjusted by the operator. It will of course be understood that in either construction shown the contiguous portions of the sides of each pair of chutes may be so pressed upon each other by means of the bolts and nuts c as to produce this desired friction.

I am aware that Patent 277,547 to Cottrell shows vibrating chutes in combination with inclined gather-boards or cant-boards and two conveyers under a construction and arrangement somewhat similar to mine; but my invention differs materially from that of Cottrell, in that, among other things, his chutes are pivoted directly to the upper edge of the center-board, which is placed between his two conveyers, each pivot being arranged about midway between the ends of the flat surface or bottom of his chute, so that when in operation one half of each chute projects downwardly below the line of the upper edge of the center-board, while in my construction each chute is suspended upon pivots, which are so far above the center-board that the chute swings free of the center-board, and the opposite ends of the chute engage alternately with the center-board and the lower edge of one of the inclined cant-boards.

What I claim is—

1. The combination, with a flour-bolt, of two conveyers arranged side by side, a center-board between the conveyers, and an adjustable chute provided with upwardly-projecting sides and pivoted by its sides above its bottom, whereby the opposite edges of its bottom may be alternately elevated to receive material, and a hopper-bottomed chamber between the chute and the bolt to receive material and deliver it alternately to opposite sides of the chute, substantially as set forth.
2. The combination, in a flour-bolt, of two conveyers arranged side by side, a center-board between the conveyers, an adjustable chute, and a hopper-bottomed chamber between the chute and the bolt to receive material and deliver it to the chute, said chute being adapted to retain its position by friction after adjustment, substantially as set forth.
3. The combination, with a flour-bolt, of two conveyers arranged side by side, a center-board between the conveyers, a series of adjustable chutes, each provided with upwardly-projecting sides, a series of supports for the chutes arranged intermediately between the ends of the conveyers, and pivots connecting the sides of the chutes with the supports, substantially as set forth.
4. The combination, with a flour-bolt, of two conveyers arranged side by side, a center-board between the conveyers, a series of adjustable chutes provided with upwardly-pro-

jecting sides, a series of transverse bars arranged intermediately between the ends of the conveyers, and pivotal supports connecting the chutes with the bars, the bars being of greater width than the spaces between two adjacent sides of two adjacent chutes, substantially as set forth.

5. The combination, with a flour-bolt, of two conveyers arranged side by side, a center-board between the conveyers, gather-boards connected with the outer casing and inclining downwardly and inwardly toward the center-board, so as to form a longitudinal throat above the center-board, a series of transverse bars supported upon the lower portions of the gather-boards, and a series of adjustable chutes, each provided with upwardly-projecting sides and pivoted by its sides to the under edges of the transverse bars, whereby the opposite edges of the bottoms of the chutes may be alternately elevated to receive material directly from the gather-boards and deliver it alternately at the opposite sides of the center-boards, substantially as set forth.

6. The combination, with a flour-bolt, of two conveyers arranged side by side, a center-board between the conveyers, gather-boards connected with the outer casing and inclining downwardly and inwardly, so as to form a longitudinal throat above the center-board, a series of transverse bars supported upon the lower portions of the gather-boards and having their lower sides grooved longitudinally, and a series of adjustable chutes, each provided with upwardly-projecting sides and pivoted by its sides within the grooves of the transverse bars, substantially as set forth.

7. In a bolting-chest, the combination of the partition C, which separates two contiguous parallel conveyer-troughs, the hopper, and cross-bars H in the bottom of the hopper, located centrally above the partition, and the oscillating chutes I I, pivoted directly to the cross-bars and arranged to swing so that their ends shall rest alternately above the partition and below the under side of the hopper, substantially as set forth.

In testimony whereof I affix my signature in presence of two witnesses.

MYRON W. CLARK.
